(57) **CLAIM**

The ornamental design for a padded face shield, as shown and described.

DESCRIPTION

FIG. 1 is a top front perspective view of a padded face shield showing our new design;

FIG. 2 is a front elevation view thereof;

FIG. 3 is a rear elevation view thereof;

FIG. 4 is a right elevation view thereof, with the left elevation view being a mirror image thereof;

FIG. 5 is a top plan view thereof;

FIG. 6 is a bottom plan view thereof; and,

FIG. 7 is a top front perspective exploded view thereof.

The broken lines shown in the drawings depict environmental structure that forms no part of the claimed invention.
